US00D421420S

United States Patent [19]

Wu

[11] Patent Number: Des. 421,420

[45] Date of Patent: ** Mar. 7, 2000

[54] **HIGH DENSITY MULTI-PORTS CONNECTOR**

[75] Inventor: **Kun Tsan Wu**, Tu-Chen, Taiwan

[73] Assignee: **Hon Hai Precision Ind. Co., Ltd.**,
Taipei Hsien, Taiwan

[**] Term: **14 Years**

[21] Appl. No.: **29/098,293**

[22] Filed: **Dec. 22, 1998**

[30] Foreign Application Priority Data

Oct. 23, 1998 [TW] Taiwan 87307743

[51] LOC (6) Cl. **13-03**

[52] U.S. Cl. **D13/147**

[58] Field of Search D13/147; 439/59,
439/61, 62, 76.1, 79, 630, 632, 634, 636,
637, 660

[57] CLAIM

The ornamental design for a high density multi-ports connector, as shown.

DESCRIPTION

FIG. 1 is a perspective view of a high density multi-ports connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
